UNITED STATES PATENT OFFICE.

WILLIAM H. FAUBER AND ALBERT M. PRICE, OF CHICAGO, ILLINOIS; SAID PRICE ASSIGNOR TO SAID FAUBER.

DESIGN FOR A FORK FOR BICYCLE OR LIKE TUBULAR FRAMES.

SPECIFICATION forming part of Design No. 33,596, dated November 20, 1900.

Application filed October 22, 1900. Serial No. 33,973. Term of patent 7 years.

To all whom it may concern:

Be it known that we, WILLIAM H. FAUBER and ALBERT M. PRICE, citizens of the United States, residing at Chicago, in the county of Cook and State of Illinois, have invented and produced a new and original Design for a Fork for Bicycle or Like Tubular Frames, of which the following is a specification, reference being had to the accompanying drawings, forming part hereof.

In the said drawings, Figure 1 is a view in side elevation of a frame-fork embodying our novel design. Fig. 2 is an edge view thereof. Fig. 3 is a cross-section of the fork-arm, taken on line 3 3 of Fig. 1. Fig. 4 is a similar cross-section of one of the arms of the fork, taken on line 4 4 of Fig. 1.

The leading or characteristic features of a frame-fork made in accordance with our novel design are as follows: The fork-arms are made smaller at their outer than at their inner ends and are joined at their inner ends by a connecting part or fork-crown. The outer side or face of each arm is composed mainly of three plane surfaces—an intermediate surface, and two lateral oblique surfaces. Said intermediate surface is widest at the outer end of the arm, extending the full width of the arm at said outer end thereof and tapers gradually toward the inner end of the arm. At said inner end of the arm the margins of said intermediate surface are brought together, or nearly so. The lateral surfaces are disposed symmetrically, one on each side of the intermediate surface, and arranged obliquely to said intermediate surface, as clearly seen in Fig. 2. The said oblique lateral surfaces are widest at the inner end of the arm, extending at said inner end of the arm from the side edges of the arm to the

central line of its outer face and taper gradually toward the outer end of the arm, where the margins thereof are brought together, or nearly so. The inner side margins of said outer oblique surfaces meet or coincide with the side margins of the intermediate flat surface, so as to form two angles at either side of said intermediate surface extending the full length of the fork-arm. The side edges of each fork-arm are equal in width to the thickness of the arm at the outer end thereof and taper gradually toward the inner end of the arm. The inner faces of the fork-arms are convexly rounded. Said convex inner faces of the fork-arms include all of the inner sides or faces of the arms except at the outer extremities thereof and parts of the side edges of the arms, and said convex inner surfaces merge into the flat edge faces thereof throughout the full length of the convex parts of the arms. At the extremities of the arms the same are substantially rectangular in cross-section, as clearly seen in Fig. 4. The rounded or convex inner surfaces of the arms are of greatest convexity at the inner ends thereof and become gradually less convexed as they approach the extremities of the arm and finally merge into the flat inner faces of the arms at the ends thereof.

What we claim as new is—

The design for a fork for bicycle and like tubular frames substantially as herein shown and described.

Signed at Chicago, Illinois, on this 18th day of October, A. D. 1900.

WILLIAM H. FAUBER.
ALBERT M. PRICE.

In presence of—

HENRY W. NORTON,
JOHN H. GLENN.
